UNITED STATES PATENT OFFICE.

MARQUIS F. SEELEY, OF FREMONT, NEBRASKA.

HOPPER.

SPECIFICATION forming part of Letters Patent No. 352,008, dated November 2, 1886.

Application filed December 9, 1885. Serial No. 185,113. (No model.)

To all whom it may concern:

Be it known that I, MARQUIS F. SEELEY, of Fremont, in the State of Nebraska, have invented certain new and useful Improvements 5 in Hoppers; and I do hereby declare that the following is a full, clear, and exact description thereof, reference being had to the accompanying drawings, and to the letters of reference marked thereon, which form a part of this specification.

This invention relates to an improvement in hoppers; and it consists in the matters herein-after described, and pointed out in the appended claims.

15 A hopper embodying the main feature of my invention is provided in its part adjacent to its exit-opening with vertical faces or walls arranged in opposition to inclined faces or walls sloping to the exit-opening, whereby liability 20 of the latter to become stopped or choked by the "bridging over" or wedging together of the material approaching the opening is obviated, as will hereinafter more fully appear.

25 A hopper embodying my invention is herein shown as applied to a corn-sheller; but the novel features of construction herein illustrated and claimed may be employed as well in hoppers adapted for use upon other machines, or for other purposes than for feeding material to 30 a machine.

The invention may be more readily understood by reference to the accompanying drawings, in which—

Figure 1 is a side elevation of a corn-sheller, 35 with a hopper embodying my invention attached, the latter being shown in central vertical section. Fig. 2 is a plan view of the part of the hopper adjacent to the exit-opening. Fig. 3 is a detail perspective view of the same.

40 In the said drawings, A is a hopper, and B is a corn-sheller, to which it is shown as attached. The said hopper, which in the particular form thereof shown is square in plan view, is provided at two adjacent sides of its 45 exit-opening with vertical walls A' A', the walls A² A³ of the hopper opposite said walls A' A' being arranged to slope downwardly to the exit-opening in the usual manner. The vertical walls A' A' will usually extend about 50 a foot or a foot and a half above the lower margins of the opposite walls A² A³, the inclined

walls A⁴ A⁵ at the sides of the bin adjacent to and above the vertical walls A' A' being constructed to slope downwardly to the upper edges of the said vertical walls in an obvious 55 manner.

In the operation of a hopper constructed as above described the ears of corn or other material resting against the vertical walls will obviously tend to move or slide freely downward, 60 so that the catching or wedging of the material cannot happen by reason of its becoming arched over between opposing inclined walls, as is liable to occur when the latter are present.

A preferred construction in means for connecting wooden hopper-walls with the metal casing of a corn-sheller or other machine, or with a spout or passage with which the hopper communicates, whereby a simple and convenient construction of the parts is obtained, is 65 70 75 herein illustrated, and is as follows: C is a metal casting adapted for attachment, by bolts or otherwise, to the margins of the inlet-opening of the corn-sheller B, or other machine, or to a spout, said casting being rectangular in plan view and provided at two of its sides with vertical parts C', extending above the flange or horizontal portion C² of the casting, and forming the vertical walls A' A' of the hopper.

In constructing the wooden parts of the hopper two of the inclined walls thereof, as A² A³, are joined at their lower margins with the lower horizontal parts of the casting, and the two opposite walls A⁴ A⁵ extend to and abut at their lower edges against the upper edges of the vertical parts C' of said casting. The said walls A² A³ A⁴ A⁵ may be sustained or supported in proper position with relation to the casting C in any manner found convenient or desirable. 80 85 90

In constructing the wooden parts of the hopper, when a casting, C, of the form described is used, the two triangular spaces at the outer vertical edges of the walls C' may be filled by triangular pieces of plank c, as shown, or by triangular extensions cast upon the walls C'. 95

I claim as my invention—

1. A hopper provided with inclined side walls and having in its lower part, adjacent to its exit-opening, opposite vertical and inclined surfaces made continuous with the said inclined side walls, substantially as described. 100

2. A hopper provided at its part adjacent to

its exit-opening with two vertical walls at contiguous sides of the opening and having inclined walls $A^2 A^3$, sloping to the exit-opening at the sides of the hopper opposite the said vertical walls, and walls $A^4 A^5$, terminating at their lower edges at the top margins of the said vertical walls, substantially as described.

3. The combination, with the wooden walls of a hopper, of a metal part, C, having two vertical side walls, C', substantially as described.

4. The combination, with the wooden walls

of a hopper, of a metal part, C, consisting of a horizontal part, C², made square in plan, and two vertical side walls, C', substantially as described.

In testimony that I claim the foregoing as my invention I affix my signature in presence of two witnesses.

MARQUIS F. SEELEY.
